CLAIM

An ornamental design for an adapter for supporting an electronic device, as shown and described.

DESCRIPTION

FIG. 1 is an illustration of a front perspective view of an adapter for supporting an electronic device;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof; and,

FIG. 7 is a bottom view thereof.

The broken lines in FIGS. 1-7 illustrate portions of the adapter for supporting an electronic device that form no part of the claimed design.
